UNITED STATES PATENT OFFICE.

LAWRENCE DENNIES, OF NEW YORK, N. Y.

DESIGN FOR A BICYCLE-BAG.

SPECIFICATION forming part of Design No. 25,618, dated June 9, 1896.

Application filed October 23, 1895. Serial No. 566,657. Term of patent 7 years.

To all whom it may concern:

Be it known that I, LAWRENCE DENNIES, a citizen of the United States, and a resident of New York, in the county of New York and State of New York, have invented and produced a new and original Design for Bicycle-Bags, of which the following is a specification.

My invention consists in a design for bicycle-bags; and it relates to the ornamental shape and configuration which will be more fully described hereinafter.

The object of my invention is to produce a novel and attractive shape for bicycle-bags, and which will give to the rider of the bicycle the appearance of being mounted upon a horse.

Figure 1 is a side elevation of a design which embodies my invention. Fig. 2 is a horizontal section of the same, taken upon the line 2 of Fig. 1.

The general shape and outline of the bag a

is that of a horse's head and neck. The rear end *c* of the bag is perfectly square. The lower end of the bag is formed on a curve *e*. In the side of the rear end of the bag is a door *g*, longer at its front than its rear edge and having ends that are inclined toward each other from the front toward the rear. In the front portion of the bag that is shaped like a horse's head is a lens *i*.

Having thus described my invention, I claim—

The design for a bicycle-bag, substantially as shown and described.

Signed at New York, in the county of New York and State of New York, this 21st day of October, A. D. 1895.

LAWRENCE DENNIES.
